UNITED STATES PATENT OFFICE.

NEIL E. SALSICH, OF BETHLEHEM, PENNSYLVANIA.

SWITCH STAND.

Original application filed May 8, 1918, Serial No. 261,629, now Patent No. 1,384,488, issued July 12, 1921.
Divided and this application filed May 9, 1921. Serial No. 468,004.

To all whom it may concern:

Be it known that I, NEIL E. SALSICH, a citizen of the United States, and residing at Bethlehem, Northampton County, State of Pennsylvania, have invented certain new and useful Improvements in Switch Stands, of which the following is a specification.

The present application which is a division of my application 261,629 filed May 8, 1918, now Patent No. 1,384,488, issued July 12, 1921, relates to railroad switch mechanism, and more particularly to switch stands therefor.

The principal objects of the invention are 15 to provide a device of the class mentioned which comprises a minimum number of simple parts and includes a target mast; to provide a dependable mechanism and one which is protected from the weather and 20 properly lubricated. A further feature of the invention consists in the combination with the above features of an adjustable arm for transmitting motion to the switch operating rod.

25 Other objects and features of novelty will be apparent from the description taken in connection with the drawings in which:

Fig. 1 is a top plan view of a switch stand constructed in accordance with the present 30 invention;

Fig. 2 is a front elevation of the stand shown in Figure 1;

Fig. 3 is a sectional elevation taken substantially on the line 3—3 of Figure 1;

35 Fig. 4 is a sectional plan view taken substantially on the line 4—4 of Figure 3;

Fig. 5 is a sectional elevation similar to Figure 3 illustrating another form of the invention; and

40 Fig. 6 is a sectional plan view taken substantially on the line 6—6 of Figure 5.

Referring to the drawings the numeral 20 indicates the base plate of the switch stand, which is shown as substantially rectangular as viewed in plan. Substantially centrally located on the plate is a raised portion forming a housing 21, which as shown in Figure 3, has an open bottom and is also open at one of the lateral edges of the plate. The actuating lever 22 is pivoted at the front of the housing, as by means of the spindle 23 rotatively mounted in the bore 24. In order to aid in holding the switch against displacement a weight 25 may be secured to the end of the lever in

any suitable manner, as by casting the weight thereon. The lever 22 is designed to occupy the position shown in Figures 1 and 2, or to be thrown over to a position opposite thereto. In either one of these positions a pad 26 is provided on the base plate for the lever to rest on, and each of these pads may have an upwardly extending lug 27 formed with an aperture 28 near the top thereof for a pin or other means to positively hold the lever against displacement.

60 The swinging motion of the lever 22 is converted into substantially rectilinear movement of the switch operating rod 29 by mechanism disposed within the housing 21. 70 As shown in Figure 3, the top wall of the housing is provided with the bosses 30 and 31 having the bore 32 in which is rotatively mounted the sleeve-like hub 33 of a bevel gear 34, the latter being disposed within the 75 housing and the hub 33 being long enough to project above the boss 30. A target mast 35 is disposed in the axial bore 36 of the hub 33, and secured thereto for rotation therewith in any suitable manner as by 80 means of the taper pin 37. As clearly shown in Figures 3 and 4, the segmental bevel gear 34 is provided with a depending lug or ear 38 disposed substantially coaxial with the axis of rotation of the gear. This lug is 85 provided with a threaded bore in which is disposed the threaded eye bolt 39, with its axis substantially at right angles to the axis of the gear 34. The pivoted end of the eye bolt 39 is connected to the switch operating 90 rod 29 by the pin 40 and transmits motion from the gear 34 to the said rod. It will be noted that the rod 29 operates through the open side of the housing and is disposed at an elevation above the bottom of the base 95 plate.

The spindle 23 projects into the housing 21 and has a square end 41 on which is mounted a segmental bevel pinion 42, a cotter pin 43 preventing axial movement of 100 this pinion in one direction on the spindle. The arrangement of the gears is such that the gear 34 is disposed above the pinion 42 and is supported by the latter against downward axial movement. Because of this arrangement no devices are required to hold the gear against downward movement, and the entire construction of the switch stand is very much simplified.

105 For the purpose of lubricating the moving 110

parts, the segmental gear 34 is formed at the top thereof with an oil reservoir 44 disposed around the boss 31 so that lubricant may pass to the bearing for the hub 33 of the gear. If desired, the teeth of the gears may be lubricated through the duct 45 formed in the gear 34. In order to supply the oil to the reservoir, the top wall of the housing is formed with an oil hole, which may be closed 10 by spring oiler 46 of any desired type.

In the form of the invention illustrated in Figures 5 and 6, the target mast provides the bearing for the upper bevel gear. Thus the housing 21 is provided with a downwardly extending boss 31 around the bore 32. The stand is also provided with an arm 50 formed with a bore 51 aligned with the bore 32, this arm being disposed below the gearing and secured to the stand, preferably being integral therewith. The target mast 35' is rotatively mounted in the bores 32' and 51 and the upper bevel gear 34' is mounted on the mast being secured thereto by the pin 37'. The gear 34' is provided 25 with a lug 38' offset from the axis of the gear and target mast, this lug carrying the threaded eye bolt 39, the axis of which is offset from the axis of the gear and substantially perpendicular thereto. The free end 30 of the eye bolt is pivotally secured to the actuating rod 29, as by means of a pivot pin 40. The gear 34' is provided with an oil reservoir 44, as described in connection with the form of Figure 3. This gear is also operated in the same manner and downward axial movement prevented by the pinion 42. It will be observed, as the target mast is secured to the gear 34', the mast in turn is secured against downward axial movement.

40 Having thus described the invention what is claimed as new and desired to be secured by Letters Patent is:

1. A switch stand including in combination, a base plate having a housing the top 45 wall of which is formed with a vertical bearing, a bevel gear within said housing having a sleeve rotatably disposed in said bearing whereby said gear is mounted for rotation about a vertical axis, a target mast secured 50 to said gear, a bevel pinion meshing with said gear disposed below the latter and means to turn said pinion.

2. A switch stand including in combina-

tion, a base plate having a housing, a bevel gear within said housing mounted for rotation about a vertical axis, an eye bolt carried by said gear adapted to be connected to the switch rod, a bevel pinion meshing with said gear disposed below the latter, and means to turn said pinion. 55

3. A switch stand including in combination, a base plate having a housing, a bevel gear within said housing mounted for rotation about a vertical axis, said gear having an axial projection within the housing, an eye bolt threaded in said projection at right angles to the axis of the gear adapted to be connected to the switch rod, a bevel pinion meshing with said gear, and means to turn said pinion. 60

65 70 75 80

4. A switch stand including in combination, a base plate having a housing, a bevel gear within said housing mounted for rotation about a vertical axis, the hub thereof having a lug, an eye bolt threaded in said lug within the housing the axis of said bolt being substantially horizontal, said bolt adapted for connection to the switch rod, a bevel pinion meshing with said gear, and means to turn said pinion.

85 90 95

5. A switch stand including in combination, a base plate having an integral housing closed at the top and open at one side, a bevel gear within the housing mounted for rotation about a vertical axis, a target mast secured to said gear and projecting through the top of the housing, a pinion disposed below said gear in mesh therewith and holding the gear against axial movement in one direction, a bolt threaded to the gear hub with its axis at right angles to the gear axis and adapted for connection to an operating rod through said open side, and means to rotate said pinion.

95 100

6. A switch stand including in combination, a base plate having a housing the top wall of which is formed with a vertical bearing, a bevel gear within said housing having a sleeve rotatably disposed in said bearing whereby said gear is mounted for rotation about a vertical axis, a bevel pinion meshing with said gear disposed below the latter and means to turn said pinion.

In testimony whereof I affix my signature.

NEIL E. SALSICH.
